ANGEL ORNAMENT

Christina Fritsche, Cincinnati, Ohio, assignor to Cincinnati Milacron Inc., Cincinnati, Ohio

Filed Nov. 21, 1972, Ser. No. 308,481

Term of patent 7 years

Int. Cl. D11—05

U.S. Cl. D29—1 B

FIG. 1 is a front elevational view of an angel ornament showing my new design, the side opposite being identical thereto;

FIG. 2 is a top plan view;

FIG. 3 is a side elevational view;

FIG. 4 is a bottom plan view; and

FIG. 5 is a sectional view taken along line 5—5 of FIG. 1.

I claim:

The ornamental design for an angel ornament, substantially as shown and described.
